UNITED STATES PATENT OFFICE.

GEORGE WORDINGHAM, OF MILWAUKEE, WISCONSIN.

SUIT-TRAY.

1,260,115.

Specification of Letters Patent. Patented Mar. 19, 1918.

Application filed January 12, 1917. Serial No. 142,120.

To all whom it may concern:

Be it known that I, GEORGE WORDINGHAM, a citizen of the United States, residing at Milwaukee, in the county of Milwaukee and 5 State of Wisconsin, have invented certain new and useful Improvements in Suit-Trays, of which the following is a specification.

It is at present customary for cleaners and dyers and sometimes tailors to deliver suits or other articles of wearing apparel to their customers in dust proof bags which house in their upper ends garment hangers upon which the articles of wearing apparel 10 are draped. The bags are usually of considerable length and much time is lost and annoyance experienced in fitting or slipping the bags over the articles of wearing apparel which have been hung and suitably 15 draped. The bags are upon the garment hanger. If the garments are bulky it is likely that the bag will be torn in efforts to slip the same downwardly over the suspended garments, and it is also likely that the garments will become 20 disarranged and therefore present an unsightly appearance when they are removed from the bag by the customer. The present invention therefore has as its object to provide a garment tray upon which the garments to be bagged may be laid and suitably 25 draped and arranged and in this manner supported against disarrangement while the bag in which they are to be housed is slipped over them and over the tray after which the 30 garments and bag may be simultaneously removed from the device without, however, in any way disturbing the arrangement of the garment. One advantage possessed by such a device lies in the fact that the garments 35 may be more readily and conveniently arranged and draped upon the hanger and another advantage is that the tray may be disposed substantially horizontal, thereby obviating the necessity of reaching above 40 one's head in passing the bag over the draped garments.

In the accompanying drawings:

Figure 1 is a perspective view of the device embodying the present invention;

Fig. 2 is a vertical longitudinal sectional view therethrough;

Fig. 3 is a vertical sectional view in detail through the lower portion of the device;

Fig. 4 is a horizontal sectional view in detail on the line 4-4 of Fig. 3.

Fig. 5 is a transverse sectional view on the line 5-5 of Fig. 2;

Fig. 6 is a transverse sectional view on the line 6-6 of Fig. 2;

Fig. 7 is a rear elevation of a modified 60 form of tray.

Briefly stated, the device comprises a tray which is supported by an arm mounted for swinging adjustment upon a base and of these parts the base is indicated by the numeral 1 and may be of any desired size and shape and this base is to possess sufficient weight to prevent overturning of the tray in any of its positions of adjustment and when garments are placed thereon. The 70 base 1 is provided upon its upper side with an integral open boss 2 within which is pivotally mounted by means of a pin 3, the lower end of the supporting arm for the tray, this arm being indicated by the numeral 4 and being provided with a right angularly extending branch 5. The manner in which the tray proper is supported by the branch 5 of the arm 4 will presently 75 be fully explained. In order that the arm 4 may be supported in various positions of adjustment, there is provided an arcuate rack comprising a curved body member 6 secured at one end, as at 7, to a lug upon the base 1 and at its other end being provided 80 with a downwardly extending portion 8 which is secured as at 9 to the boss 2, the body 6 describing a quarter of a circle as clearly shown in Figs. 2 and 3 of the drawings. The pivotal connection between the 85 lower end of the arm and the boss 2 is a relatively loose one so that the arm may be swung slightly laterally and in such movement the portion 4 of the arm may be brought into and out of engagement in diagonal notches 10 formed in that lateral edge of the rack 6 beside which the arm 4 swings. In the present instance the rack is provided with three of the notches and for 90 convenience in describing the use of the device these notches are designated in the drawings specifically by the reference numerals 10^a, 10^b, and 10^c, the notch 10^a being located near the first-mentioned end of the rack 6, the notch 10^c being located near the upper end of the arcuate portion of the rack, and the notch 10^b being located between the notches 10^a and 10^c. It will now 105 be apparent that the arm 4 may be engaged in the notch 10^a so as to assume an approxi-

95

100

105

110

mately horizontal position, or it may be engaged in the notch 10^b when it will assume an inclined position, as illustrated in Fig. 3 of the drawings, or, if desired, the 5 arm may be engaged in the notch 10^c in which position the arm will be substantially upright. In order that the arm may be held upright, or in other words, may be held in engagement in the notch 10^c , a sliding latch 10 11 is mounted upon the underside of the arcuate portion of the rack at the upper end thereof and has a shank 12 fitting slidably through an opening 13 formed in the portion 8 of the said rack near its upper 15 end. The latch is guided by a pin 14 which is fitted through a slot 15 formed in the shank of the latch and secured in the said arcuate portion of the rack. A spring 16 is fitted through the said shank of the latch 20 and bears at one end against the portion 8 of the rack and at its other end against a shoulder 17 upon the said shank and this spring serves to normally hold the latch slid in a forward direction as shown in 25 Figs. 3 and 4 of the drawings. The latch is provided in its forward end with a transverse head indicated by the numeral 18 and one end of this head is designed to extend normally substantially across the throat of 30 the notch 10^c so as to practically close this notch and, when the arm 4 is in engagement in the notch, the latch head 18 will bear against the said arm and be firmly held against disengagement from the notch. Of 35 course, when the arm 4 is in engagement in either of the notches 10^a or 10^b the weight of the arm and the tray supported thereby will prove sufficient to prevent accidental disengagement of the arm from the notch. 40 The tray comprises a frame including side bars 19, a cross bar 20 connecting the inner ends of the side bars, a cross bar 21 connecting the outer ends of the side bars, and an intermediate bar 22 which extends centrally between the bars 19 and in parallelism thereto. 45 The bars 20 and 21 respectively, carry brackets 23 and 24 and these brackets respectively, are provided with sleeve portions 25 and 26 through which the ends of the bar 22 are fitted, as shown in Figs. 1, 2 and 6 of the drawings, it being understood that the bar 22 is not slideable through the sleeve portions 25 and 26 but that the entire frame structure is rigid. It will be observed, particularly by reference to Fig. 2, that the sleeve portions 25 and 26 are displaced with relation to the plane occupied by the side bars and end bars of the frame and that, consequently, the bar 22 is located forwardly of 50 the said plane, or, assuming that the tray is in horizontal position, is located below the said plane. The inner end of the bar 22 projects inwardly beyond the sleeve portion 25, as indicated by the numeral 27 and is 55 fitted in one end of an elbow 28 at the outer

end of the portion 5 of the arm 4. Thus while the frame as a whole is displaced rearwardly with relation to the arm 4, the said arm and frame occupy parallel planes. The bottom of the tray is in the nature of a sheet 30 of press board or any other material possessing the desired degree of stiffness and yet sufficiently flexible to permit of its being stretched within the frame in the following manner. The side bars 19 are formed each with a longitudinally extending groove 31 and the lateral edge portions of the sheet 30 are carried around the said side bars and fitted into the grooves 31 in the manner clearly shown in Fig. 6 of the drawings, the intermediate portion of the sheet 30 being passed beneath or in front of the bar 22 and the sheet being stretched taut. In order to prevent any undue sagging of the bottom of the tray and in order to further relatively brace the side bars 19, an intermediate cross bar having relatively angularly extending portions 32 is secured at its bend, as at 33, to the forward side of the bar 22 and the ends of the said portions 32 abut against the opposing sides of the side bars 19 and are secured in place by any suitable means as, for example, by screws 34 which are passed through the side bars 19 and threaded into the said ends of the portions 32 of the cross bar. 95

In order that a coat hanger may be readily assembled with the tray after the garments have been disposed upon the hanger, the upper or outer end of the bar 22 is provided, 100 beyond the sleeve portion 26 of the bracket 24, with an outwardly and rearwardly extending finger 35 which in its extremity is formed with a notch 36, the said notch being designed to receive the usual garment hanger hook. 105

From the foregoing it will be understood that after garments have been casually hung upon a garment hanger the garment hanger may have its hook engaged in the notch 36 of the finger 35 with the garments resting upon the bottom 30 of the tray. In this operation the tray may assume an inclined position, as shown in the several figures of the drawings, or it may occupy a horizontal 110 position to suit the convenience of the user of the device. The garments are then carefully draped and otherwise arranged so that they will present a neat appearance and no undesirable creases will be likely to be 115 formed therein. After arranging the garments the bag in which they are to be delivered to the customer, and which, being of well-known construction is not here shown, is slipped over the outer end of the tray and 120 passed over the tray and over the said garments until the finger 35 and the hook of the garment hanger are projected through the opening in the closed end of the bag. 125 The hook of the garment hanger may then 130

be grasped and the hanger, together with the garments suspended thereon, may be removed from the tray without in any way disarranging the said garments or without 5 likelihood of tearing the bag. When the device is not in use the tray may be swung to upright position and will then occupy but little space.

If desired the bottom of the tray may be 10 constructed as shown in Fig. 7 of the drawings. In this modification the sheet constituting the said bottom is passed in front of the intermediate bar 22 of the frame of the tray and thence about the rear sides of 15 the side bars 19 and a lacing cord or string 37 is threaded back and forth through eyelets 38 in the edges of the said sheet, and, of course, when this cord is drawn taut the sheet will be properly stretched.

20 Having thus described the invention, what is claimed as new is:

1. In a device of the class described, a tray comprising a frame, means supporting the frame at one end thereof, the said frame including side members, a tray bottom comprising a sheet connected at its lateral edges with the said side members and stretched taut between the same, and means carried by the tray for the support of a garment hanger. 25

2. In a device of the class described, a tray comprising a frame, means supporting the frame at one end thereof, the said frame including side members, a tray bottom comprising a sheet connected at its lateral edges 30 with the said side members and stretched taut between the same, and means at the other end of the tray for the support of a garment hanger.

35 3. In a device of the class described, a tray comprising a frame including side members and an intermediate member displaced with relation to the plane occupied by the side members, a tray bottom comprising a sheet

stretched over the said intermediate member and connected at its lateral edges with 45 the side members of the frame, and means at one end of the frame for supporting the same.

4. In a device of the class described, a tray comprising a frame including side members 50 and an intermediate member displaced with relation to the plane occupied by the side members, a tray bottom comprising a sheet stretched over the said intermediate member and connected at its lateral edges with the 55 side members of the frame, means at one end of the frame for supporting the same, and means at the other end of the frame for supporting a garment hanger.

5. In a device of the class described, a 60 base, an arcuate member mounted thereon and having a plurality of recesses, an arm loosely pivotally mounted upon the base and angularly movable beside the said arcuate member and designed for engagement in 65 the recesses selectively, a suit tray supported at its lower end by the said arm, and means at the upper end of the tray for the support of a garment hanger.

6. In a device of the class described, a tray 70 having its upper surface transversely concave to receive garments to be bagged, means for supporting the tray for angular adjustment, and an element extending from the upper end of the tray at the concave side 75 thereof for the attachment and support of a garment hanger.

7. In a device of the class described, a tray to receive garments to be bagged, means connected with the lower end of the tray for 80 angular adjustment thereof, and a finger extending from the upper end of the tray in an upward direction and arranged for the connection and support of a garment hanger.

In testimony whereof I affix my signature. 85
GEORGE WORDINGHAM. [L. S.]
